Patented Sept. 16, 1919.

UNITED STATES PATENT OFFICE.

FRANK W. HOWARD, OF NEW YORK, N. Y.

RAINCOAT.

1,316,364.

Specification of Letters Patent. Patented Sept. 16, 1919.

Application filed January 6, 1917. Serial No. 140,864.

To all whom it may concern:

Be it known that I, FRANK W. HOWARD, a citizen of the United States, and a resident of New York city, in the county of New York and State of New York, have invented certain new and useful Improvements in Raincoats, of which the following is a specification.

This invention relates to raincoats which 10 comprise a cape and a skirt, and the invention contemplates forming portions of these parts by means of flaps formed integrally with the coat. The general object of the invention is to produce a raincoat of this 15 type which is very simple in construction, and which is formed in such a way that the coat can be produced from a relatively narrow piece of goods. While many features of the raincoat are applicable to coats constructed of any material whatever, the invention has special advantages when applied to a raincoat constructed of water-proof paper. This material though is frangible and liable to tear. According to my invention, however, 20 I provide a form for the raincoat which will minimize the strains to which its parts will be subjected.

Further objects of the invention will appear hereinafter.

30 In the drawing which fully illustrates the preferred embodiment of my invention—

Figure 1 is a front elevation and partial section showing the complete raincoat;

Fig. 2 is a plan of a blank element from 35 which this raincoat may be conveniently constructed, the lower portion of this view being broken away;

Fig. 3 is a plan of the complete blank ready to be formed into the raincoat; and 40 Fig. 4 is a vertical section taken on the line 4—4 of Fig. 1.

Referring more particularly to the parts, the raincoat comprises a cape 1 having shoulders 2, and a centrally disposed neck 45 opening 3. The lower portion of the raincoat is in the form of a skirt 4 which envelops the lower portion of the body. The forward portion of the raincoat has edges 5 and 6 which overlap each other at the 50 front. At the neck opening 3 the edge of the material is turned over so as to form a hem 7, and in this hem is secured a cord 8, the ends of which extend from the garment at the front so that they can be attached 55 in a bow 9.

At the sides of the raincoat as indicated at the points 11, Fig. 1, gaps are formed to produce armholes, and at each side of the front of the garment the sides of the skirt are supported by connecting means or flaps 60 12 which extend upwardly from the skirt, the upper ends of the said flaps 12 being attached at an elevated point as at 13 to the under side of the cape. In this way arm spaces are formed in front of each of the 65 flaps 12 under the cape. The cape 1 and the skirt 4 are formed by means of integral flaps 14 and 15 between which the arm hole gaps 11 are formed, and these gaps have re-entrant angles 16 between the flaps. In order to prevent the material from tearing 70 at these reentrant angles I prefer to provide the vertex of each angle with a small sheet 17 of adhesive paper or cloth, which is made to adhere throughout substantially its entire 75 surface to the raincoat at this point, and if desired this may be at the vertex 18 of the angle. I prefer to connect the flaps 12 to the cape by means of strips 19 of adhesive cloth or paper (see Fig. 4). 80

The skirt-flaps meet at the front to form the skirt; and so do the cape-flaps, to form a cape crossing the front and covering the upper portion of the skirt at the front.

In order to hold the raincoat closed at the 85 front I prefer to provide buttons 20 of cardboard which are secured by central eyelets 21 passing through and riveted in the forward portion of the cape at connecting strips 19. The skirt of the raincoat is provided 90 with similar buttons 22, the central eyelets of which pass through reinforcements consisting of small square sheets 23 of adhesive paper or cloth. The buttons are arranged in opposite pairs, as shown, and each pair of 95 buttons is provided with a cord 24 attached to one of the buttons and capable of being wound around the eyelet of the button on the opposite edge of the raincoat.

A raincoat such as that described is preferably constructed from an elemental blank such as the elemental blank 25 illustrated in Fig. 2. This blank may be cut from a web of material of relatively narrow width, the edge of which is indicated by the dotted line 26 coinciding with the extreme side edges of the blank. This blank 25 is formed at its upper portion with an integral cape flap 26, the outer and upper portion of which preferably has a curved edge 27 which termi- 100 105 110

nates at its lower portion in an ogee curved edge 28. The blank also has an integral laterally extending skirt flap 29, the outer edge 30 of which coincides with the edge 26^a 5 of the web of material from which the blank is formed.

Between the cape flap 26 and the skirt flap 29 a gap 31 is formed which is to produce the armholes which occur at the points 11 10 of the finished raincoat. The gap 31 produces a reëntrant angle 32 between the flaps 26 and 29.

In order to give more freedom of movement at this point and also to afford material in the cape to project beyond the arm opening to protect the arm, I prefer to provide the reëntrant angle 32 with a small substantially horizontal slit 33, terminating near the inner edge of the blank, so that 20 the vertex of the reëntrant angle 32 is practically formed at the point 34 where this slit terminates. In this way I produce a protecting flap 32^a which will project over the armhole at 11. This point 34 in the blank 25 becomes the point 18 of the finished raincoat. Before forming this slit 33 I prefer to attach to the blank the reinforcing sheet 17 referred to above. This part 17 prevents the slit extending any farther. The upper 30 edge 35 of the skirt flap 29 is preferably substantially horizontal and from this upper edge the connecting flap 12 referred to above, extends upwardly. This flap is preferably formed integrally from the flap 29.

35 At the upper portion and adjacent the inner edge 36 of the elemental blank I provide a rectangular notch 37 with a small inclined incision 38 at the vertex of the angle. From the upper portion of this notch an inclined straight edge 39 extends, and this edge 39 is to form one of the front vertical 40 meeting edges 5 or 6 of the cape of the finished raincoat.

In order to form the complete blank 40, 45 see Fig. 3, I unite two elemental blanks such as that shown in Fig. 2, and I connect them by gluing or sewing, so as to form two side portions connected by a back seam 41 of approximately the depth indicated by the 50 dotted line 42 in Fig. 2. This seam preferably does not extend throughout the entire length of the coat, but I leave a vent 43 at the bottom, at which point the unattached hems 44 are bent back and glued or sewed 55 to their adjacent part of the blank. The notches 37 of the elemental blanks come together to form a substantially rectangular gap 45 which forms the neck opening 3 of the finished raincoat. In forming this gap 60 the edges are turned down so as to form the hems 7 referred to above, in which the cord 8 is carried.

In order that the skirt of the raincoat will adapt itself to the form of the body I prefer to form the blank with a plurality of

vertical creases 46. In forming the raincoat the spaces between the creases 46 operate like pleats. When the raincoat is formed from the blank the shoulder lines extend from the corners 47 of the neck gap or notch 70 45, and the cape flaps extend around to the front so as to form a complete cape. The skirt flaps 29 also extend around to the front of the garment.

It is understood that the embodiment of 75 the invention set forth herein is only one of the many embodiments the invention may take, and I do not wish to be limited in the practice of the invention nor in my claims, to the particular embodiment set forth. 80

What I claim is:

1. A raincoat comprising two side portions connected together by a seam at the back of the coat, said side portions each having an integral cape-flap at its upper 85 portion extending around to the front of the raincoat to form a cape, and having an integral skirt-flap also extending around to the front of the raincoat to form a skirt, the said cape-flap and said skirt-flap of 90 each side portion having a reëntrant angle therebetween, a reinforcing piece consisting of an adhesive sheet attached to said raincoat at the vertex of the said reëntrant angle, said raincoat having a gap at each side to form an armhole, and each skirt portion having an upwardly extending integral connecting flap connected to the under side of the cape at an elevated point, and thereby forming an arm space in front of 100 each connecting flap under the cape.

2. A raincoat having an upwardly disposed integral cape-flap to form a cape, and having an integral lower skirt-flap to form a skirt, said raincoat having a gap 105 formed between said cape and skirt, constituting an armhole, said raincoat having a reëntrant angle formed therein at said gap, and a piece of adhesive sheet substantially the entire surface whereof adheres 110 to said raincoat at said angle.

3. A raincoat having oppositely disposed integral cape-flaps at its upper portion extending around to the front of the raincoat to form a cape, and having integral skirt-flaps also extending around to the front of the raincoat to form a skirt, said raincoat having a reëntrant angle formed between the cape-flap and the skirt-flap at each side 115 of the raincoat to produce an armhole, said skirt-flaps at the front of the raincoat having upwardly extending connecting flaps, and a piece of an adhesive sheet at each side adhering to the under side of the cape, and to the upper end of the adjacent connecting 120 flaps to support the forward portion of the skirt from the cape.

4. An elemental blank for a raincoat, having a cape-flap formed at its upper portion, said cape-flap having a substantially rec- 125

tangular notch formed at one edge thereof, and having an inclined edge extending from said notch to form the front vertical edge of the cape, said blank further having a laterally extending skirt portion at its lower part to extend around and form the front skirt portion of the raincoat, the upper portion of said skirt-flap having an upwardly extending connecting flap to be connected to the under side of the cape.

5. A blank for forming a raincoat having two oppositely disposed cape-flaps, the upper portion of said blank at said cape-flaps having a substantially rectangular notch formed therein, said cape-flaps having inclined edges extending from said notch to form the vertical front edges of the cape, the lower portion of said blank being constructed to form the skirt of the raincoat

10 and having flaps to be connected to the under side of the cape.

6. A blank for a caped raincoat consisting of two pieces having a substantially straight edge meeting to form a central seam, each of said pieces having a cape flap 25 formed at its upper portion extending laterally away from said central seam, to extend around to the front of the raincoat and form a portion of the cape, each of said pieces also having a laterally extending 30 skirt flap at its lower part to extend around and form a portion of the skirt of the raincoat.

Signed at New York, in the county of New York and State of New York, this 28th 35 day of Dec., A. D. 1916.

FRANK W. HOWARD.
